SEWERAGE SYSTEM

Victor Wachta, Hammond, Ind., assignor to General Drainage & Pipe Cleaners, Inc., Hammond, Ind., a corporation of Indiana

Application September 27, 1947, Serial No. 776,576

7 Claims. (Cl. 182—2)

1

This invention relates to improvements in sewer and drainage systems employed in city streets, and has for its principal object to provide means for relief of drainage problems arising from sudden heavy rains.

The sewerage systems employed in municipalities have become more or less standardized in arrangement, to include a network of main sewer lines disposed along street centers, and communicating with catch basins centrally disposed at street intersections or at intermediate points, each of said catch basins including a manhole with a removable cover. Water from the gutters is led through drains located along the gutters, usually at corner intersections and communicating through pipe lines to the central catch basins. Sewerage outlets from buildings along the street are led into the main sewerage lines at suitable points between adjacent street intersections.

It is a common occurrence for the sewer lines to become rapidly overloaded and to back up during sudden downpours of rain. It has been shown that these difficulties are not merely due to inadequacy in the size of the main sewers or conduits employed in the sewerage system, but is usually attributable in large measure to the arrangement of the sewer lines, catch basins and lead-in conduits to the system, whereby air or gas pockets are formed in the main sewer lines which have a tendency to choke and otherwise interfere with the proper flow and discharge of water when the sewers become overloaded by sudden rains.

In present day sewer systems, the catch basins at sewer line intersections are wholly inadequate for relieving the sewer lines of air or gas pockets which tend to choke the system, because of their limited capacity. In practice, it has often been demonstrated that the average sewerage system is only capable of carrying off but a small proportion of the water as compared with its theoretical capacity based upon the size of the sewer lines, conduits and catch basins. As a result, many cities find it necessary to install expensive storm sewer systems, in addition to the usual drainage systems.

In carrying out my invention, I provide an improved system employing as its principal features a novel form of relief and expansion catch basin used at main sewer line intersections at street corners or other suitable intervals, and in association with each relief expansion catch basin I provide drainage inlets and auxiliary reservoirs designed to hold excessive water temporarily during a heavy rain or flash flood. These

2

auxiliary reservoirs are provided with a siphon system arranged to evacuate most of the water from each reservoir into the main sewerage system, after each excessive rainfall, so as to put said auxiliary reservoirs in condition for the next heavy rain.

My invention may best be understood by reference to the accompanying drawings, in which:

Figure 1 is in part diagrammatic, to illustrate a typical fragmentary portion of the sewerage system as applied to a city street.

Figure 2 is an enlarged fragmentary detail view of the sewerage system at one street intersection, with the basins shown in horizontal section.

Figure 3 is a vertical section taken along the longitudinal axis of the system shown in Figure 2.

Figure 4 is a vertical section similar to that shown in Figure 3 but illustrating a modified arrangement of the siphon system.

Referring to the illustrative arrangement of the sewerage system shown in the drawings, 10 indicates the main sewer lines or conduits which may be laid as usual along each street at or near the center thereof. These main sewer lines lead into main catch basins 11, 11 at each corner intersection as indicated. Similar intermediate catch basins can, of course, be provided between adjacent street intersections, if desired. The main sewer lines 10, 10 are laid with the usual inclination in one direction for proper drainage.

A plurality of intercepting discharge lines 12, 12 from homes, factories or the like, lead directly into the main lines 10, 10 intermediate the catch basins 11, 11.

Each main catch basin may be made as usual of masonry with an opening 13 at the top, closed as usual by a manhole cover 14 flush with the surface 15 of the street. The street is also provided as usual with curbs 16, 16.

At suitable positions at or near the curbs 16, 16 are provided a plurality of drainage reservoirs 20, 20, each having an opening 21 at its top covered by a suitable grill 22, designed to permit ready drainage of water from along the curbing into said reservoir.

Each of the auxiliary reservoirs 20, 20 drains into an adjacent main catch basin by an inclined conduit 23 which opens from the auxiliary reservoir at a point considerably above its bottom, and likewise discharges into the catch basin at a point considerably above the bottom of the latter.

Although a very similar arrangement of intersecting sewer lines, central catch basins and auxiliary reservoirs have heretofore been com-

monly employed in sewerage systems, it will be understood that with such previous systems both the central catch basins and the auxiliary reservoirs were for cleaning purposes only, and have uniformly been very much smaller in comparison with the size of the main sewer pipes or conduits, which determine to a large extent the normal capacity of the system. For instance, assume that the main sewer pipes 10, 10 are approximately 24 inches inside diameter, which is standard for many municipal systems, the central catch basin employed therewith usually is in the neighborhood of 3 feet in diameter, that is to say only slightly larger than the manhole cover used therewith. Previous sewerage systems also have employed drainage lines from inlets adjacent the curbing, but such inlets usually consist of relatively small grills over small silt traps, each having a total capacity of but a few gallons.

In my improved system each central catch basin 11 has a vastly increased capacity in comparison to the size of the main sewer lines. For instance, in the form shown herein, the central basin is approximately 12 feet in diameter for a height of approximately 5 feet near its bottom and tapers upwardly from its enlarged bottom portion to the manhole cover 14, as shown. The total capacity of each catch basin will depend upon the depth of the basin, which is varied, depending upon the depth of the main sewer lines 10, 10 with which it is connected, but in any case, its capacity is many times greater than that of catch basins which have heretofore been employed, as will hereinafter be more fully set forth.

The auxiliary reservoirs 20, 20 are likewise formed with a far greater capacity than has heretofore been employed in sewerage systems. For instance, in the form shown each of said auxiliary reservoirs has a maximum diameter of 8 feet for a height of 5 feet and tapering upwardly therefrom to the cover or grill 22 as shown.

The connecting conduits 23, 23 from the auxiliary reservoirs 20, 20 to their associated catch basin 11 may, for instance, consist of 8 inch inside diameter pipes, although the exact size of these conduits is not especially critical. In the preferred form shown the bottom of each of the auxiliary reservoirs 20, 20 is disposed somewhat above the level of the bottom of the associated central catch basin 11, a sufficient distance to insure proper drainage, and also to permit venting of air or gas from above the water level in the central basin 11, through the conduits 23 and reservoirs 20. For instance, in the form shown in Figure 2 the bottom of each auxiliary reservoir may be approximately 1 foot above the top of the adjacent main sewer line system consisting of the main line pipes 10, 10.

In connection with each of the auxiliary reservoirs 20, 20 I provide a siphon pipe 24, having one end disposed slightly above the bottom thereof and having the other end leading into the main sewer system. In the form shown in Figure 2 the siphon is disposed along and within the discharge pipe 23 leading to the main catch basin 11 so that the lowermost end of the siphon discharges directly into said catch basin, as shown. With this arrangement it will be understood that each of the auxiliary reservoirs 20, 20 will serve to receive relatively large quantities of water during a heavy rain or flash flood, and when full the water will be emptied therefrom through the discharge tube 23 into the catch basin 11. Thereafter the siphon 24 will operate automatically to

discharge the water from said auxiliary reservoir to a point near the bottom of the latter.

It will be understood, of course, that the open end of the siphon within the auxiliary reservoir must be higher than the end of the siphon where it discharges into the central catch basin 11. In the form shown in Figure 3 the intake end of the siphon 24 may be approximately 12 inches above the bottom of the auxiliary reservoir while the discharge end of the siphon may be approximately 2 feet lower.

The arrangement of the siphon 24 shown in Figure 3 where it is led through the discharge pipe 23 affords an especially simple construction since the siphon can be readily installed in the system with a minimum of labor and can also be readily removed or replaced, and can be cleaned from either end. In the modified form of siphon 25 shown in Figure 4, the siphon pipe 20 is led directly from the auxiliary reservoir 20 to one of the adjacent main line pipes 10 instead of being passed through the outlet pipe 23 leading from said auxiliary reservoir. This arrangement of siphon 25 shown in Figure 4 provides an auxiliary air vent to the main sewer line 10 at a point comparatively remote from the central catch basin so as to assist in relieving air or gas pockets which otherwise may tend to form in the main line 10.

Although the capacity and shape of the auxiliary reservoirs 20, 20 may be varied from that shown and described herein, it will be understood that said reservoirs are preferably made sufficiently large to receive and store, temporarily, any amount of water in excess of the normal capacity of the sewerage system, particularly in cases of sudden rains or flash floods so as to hold enough of the excess water back to give more time for the entire sewerage system to adjust itself to flood conditions, as will hereinafter more fully appear.

Similarly, the catch basins, 11, 11 may vary in size and shape from that herein shown and described, but in practice I find that the capacity of each catch basin should preferably be at least substantially equal to the total capacity of the main line sewers 10, 10 with which it is directly connected. Where this preferred relationship is maintained each catch basin 11 will serve as a prompt relief for any water that may tend to be temporarily discharged or backed up thereinto from any one of the connected main sewer lines.

The operation of my improved sewerage system may now be explained as follows:

Referring first to the function of the relief catch basins 11, 11, in my improved system it will be understood that in the normal operation the main sewerage lines 10, 10 are of ample capacity to discharge sewage from homes, office buildings, factories and the like, by gravity flow, with the sewage occupying but a small portion of the diameter of the several sewer lines. In case of a sudden rainfall however, the rain water from the streets rushes into the system through the gutter drains and also through the intersecting drainage lines connected directly with the main lines 10, 10 so as to disturb the normal flow through the sewerage system at the moment the latter is called upon to take care of a greatly increased flow. The added influx of water takes place quite irregularly throughout the system; for instance, there may be a much greater influx through certain of the intercepting discharge lines 12, 12 near opposite ends of a single main conduit 10 than toward the middle portion of said conduit. Also

certain overlying areas may tend to drain quicker than other areas so as to overload certain of the main sewer lines 10, 10 before others.

As a result of this sudden uneven discharge of water into the main lines, which shortly before were only partially filled with water, there is a tendency for the system to become choked, due to turbulences, attended with the entrapment of gas pockets at localized points along the main line conduits, to a degree that the "pushload" is insufficient to produce flow in the normal direction of drainage. Consequently, the entire system may be backed up and choked at several points, so as to be rendered practically ineffective for a considerable period of time. Accordingly, means must be provided for relieving the gas pockets as soon as they form, so that the sewerage system may readjust itself quickly to its proper operating conditions, for discharge of the accumulated water at full capacity.

I find that by providing relief and auxiliary chambers 11 and 20 of sufficient size, as herein shown and described, it is possible to eliminate almost instantly such gas pockets, with their attendant difficulties above described.

The large relief chambers 11 are so arranged as to permit the water in each length of main pipe 10 connected thereto, to readjust itself promptly to flow in the proper direction, by permitting any air pockets in individual mains to be quickly discharged and relieved at either end, in one chamber or another (in some cases, backing up, momentarily, if necessary, against the normal direction of flow) until the proper flow to the full capacity of each main is established throughout the system. In this manner any local blocks will be quickly alleviated, and the system will promptly begin to function to its full capacity, draining in the proper direction.

During the readjustment of the flow the level of the sewage in the large catch basins 11, 11 will of course rise to a considerable height; in fact, the catch basins may become completely filled with water at times, but the water lever will again resume its normal height after the emergency has passed.

The auxiliary reservoirs 20, 20 cooperate with the catch basins 11, 11 and the remaining parts of the sewerage system in the following manner; in the case of a sudden rain said reservoirs are sufficiently large and deep to receive a large portion of the rain before any of the water starts to drain through the connecting pipes 23, 23 adjacent catch basin 11. In this manner the initial flood of water from a rainstorm is held back a sufficient length of time to permit the rain water which is discharged directly from buildings, etc., into the main line conduits 10, 10 to fill said main line conduits and readjust the flow therealong by eliminating the air or gas pockets therefrom, before any substantial flow of water is discharged from the reservoirs 20, 20 into the catch basins 11. The connecting pipes 23, 23 are arranged to discharge into the main catch basin 11 at a relatively high level so as to permit air or gas which may accumulate in the catch basin to escape into the outer air through pipes 23 and reservoirs 20, thereby relieving pressure on the manhole cover 14 of the main catch basin 11 and eliminating danger from manhole explosions which often occur with conventional sewer systems.

I have found that any air or gas pockets in the main conduits 10, 10 can be relieved much more effectively when there is a minimum

amount of water in the bottom of the catch basins 11, 11 to permit rapid expansion or flow from said conduits as may be required to relieve the latter.

After the main conduits 10, 10 have been relieved of air pockets and the normal flow of water has been established to full capacity through said conduits any amount of water can be discharged from the auxiliary reservoirs 10 through pipes 23, 23 into the adjacent catch basins 11, 11 without interfering with the normal flow of water through the system.

After the rainstorm has ceased each of the reservoirs 20, 20 will continue to be drained 15 through the pipes 23, 23 until the water lever has reached the opening of said pipes. Thereafter the siphons 24, 24 will be called into operation to continue the draining of the several auxiliary reservoirs to a point near the bottom of each. The 20 reservoirs will then be substantially empty ready for receiving the next sudden influx of water as before.

By utilizing the novel principles herein disclosed and described, it is possible to increase the 25 capacity of a sewer system using the same size main sewer lines by as much as two and one-third times the capacity attained by sewerage systems of a conventional type. In many instances it will be found that this added capacity 30 will be sufficient to take care of all excessive loads, thereby rendering the use of auxiliary storm sewer systems unnecessary.

Although I have shown and described certain steps and forms of my invention, it will be understood that I do not wish to be limited to the exact construction shown and described, but that various changes and modifications may be made without departing from the spirit and scope of the invention as defined in the appended claims.

40 I claim:

1. In an underground sewerage system, a network of main sewer lines with catch basins at intersections thereof, said main sewer lines having a plurality of drainage connections at various 45 points therealong, said catch basins having sufficient capacity to receive substantially the full volume of the main sewer lines connected thereto, drainage reservoirs connected to said catch basins through an outlet opening substantially above the bottom of each reservoir, the total capacity of the reservoirs below their outlets connected to each of said catch basins being sufficient to hold back the water received in said reservoirs from a sudden rain for a period of 50 time to permit substantial evacuation of gas pockets from said lines by expansion into said catch basins, and siphon pipes arranged to evacuate sewage from said reservoirs from below the level of their respective outlets into lower points 55 in said sewerage system.

2. In an underground sewerage system, a network of main sewer lines with catch basins at intersections thereof, said main sewer lines having a plurality of drainage connections at various 60 points therealong, said catch basins having sufficient capacity to receive substantially the full volume of the main sewer lines connected directly thereto, drainage reservoirs connected to said catch basins through an outlet opening substantially above the bottom of each reservoir, the total capacity of the reservoirs below their outlets connected to each of said catch basins being sufficient to hold back the water received in said reservoirs from a sudden rain for a period of 65 time to permit substantial evacuation of gas 70 pockets from said lines by expansion into said catch basins, and siphon pipes arranged to evacuate sewage from said reservoirs from below the level of their respective outlets into lower points in said sewerage system.

gas pockets from said lines by expansion into said catch basins, and siphon pipes extending through said outlets arranged to evacuate sewage from said reservoirs from below the level of their respective outlets into lower points in the adjacent catch basin.

3. In an underground sewerage system, a network of main sewer lines with catch basins at intersections thereof, said main sewer lines having a plurality of drainage connections at various points therealong, said catch basins having sufficient capacity to receive substantially the full volume of the main sewer lines connected directly thereto, drainage reservoirs connected to said catch basins through an outlet opening substantially above the bottom of each reservoir, the total capacity of the reservoirs below their outlets connected to each of said catch basins being sufficient to hold back the water received in said reservoirs from a sudden rain for a period of time to permit substantial evacuation of gas pockets from said lines by expansion into said catch basins, and siphon pipes arranged to evacuate sewage from said reservoirs from below the level of their respective outlets into lower points in an adjacent main sewer line.

4. In an underground sewerage system, a network of main sewer lines with catch basins at intersections thereof, and drainage reservoirs each connected to said catch basins through a duct having an outlet opening disposed substantially above the bottom of said reservoir to form a storage basin below said outlet, and a siphon pipe arranged to evacuate the sewage from said storage basin into a lower point in said sewerage system.

5. In an underground sewerage system, a network of main sewer lines with catch basins at intersections thereof, and drainage reservoirs each connected to said catch basins through a duct having an outlet opening disposed substan-

tially above the bottom of said reservoir to form a storage basin below said outlet, and a siphon pipe extending through said outlet arranged to evacuate the sewage from said storage basin into a lower point in the adjacent catch basin.

6. In an underground sewerage system, a network of main sewer lines with catch basins at intersections thereof, and drainage reservoirs each connected to said catch basins through a duct having an outlet opening disposed substantially above the bottom of said reservoir to form a storage basin below said outlet, and a siphon pipe connected directly to an adjacent main sewer line at a lower point arranged to evacuate the sewage from said storage basin into said sewer line.

7. In an underground sewerage system, a network of main sewer lines with catch basins at intersections thereof, and drainage reservoirs each connected to said catch basins through a duct having an outlet opening disposed substantially above the bottom of said reservoir to form a storage basin below said outlet, and a siphon pipe connected directly to an adjacent main sewer line at a lower point arranged to evacuate the sewage from said storage basin into said sewer line, and also providing an auxiliary air vent for the latter.

VICTOR WACHTA.
